WILLIAM H. KELLER, OF GRAND HAVEN, MICHIGAN, ASSIGNOR TO KELLER PNEUMATIC TOOL COMPANY, OF GRAND HAVEN, MICHIGAN, A CORPORATION OF MICHIGAN.

PRESSURE-FLUID-ACTUATED TOOL.

1,329,774.

Specification of Letters Patent.

Patented Feb. 3, 1920.

Application filed April 27, 1918. Serial No. 231,060.

To all whom it may concern:

Be it known that I, WILLIAM H. KELLER, a citizen of the United States, residing at Grand Haven, in the county of Ottawa and

5 State of Michigan, have invented certain new and useful Improvements in Pressure-Fluid-Actuated Tools, of which the following is a specification.

The invention relates to pressure-fluid-actuated tools, and the general object thereof is to provide a tool of improved construction and arrangement which may be manufactured at a minimum cost.

A more specific object of the invention is 10 to provide valve mechanism, of improved construction, for pressure - fluid - actuated tools.

A further object of the invention is to provide improved valve mechanism for 15 tools of the so-called "one-piece" type.

The objects of the invention thus generally stated, together with other and ancillary advantages, are attained by the construction and arrangement illustrated in the 20 accompanying drawings forming part hereof, in which Figure 1 is a longitudinal central sectional view through, a pneumatic hammer embodying the features of the invention, showing the valve in one position.

25 Fig. 2 is a fragmentary longitudinal sectional view showing the valve in another position.

The tool comprises a cylinder 1, a handle 2 mounted upon the rear end of the cylinder, 30 a piston 3 operable within the cylinder, and valve mechanism 4 mounted within the rear end of the cylinder and arranged to control the movements of the piston 3.

The cylinder 1 is preferably made of a 35 round piece of metal of substantially uniform external diameter throughout, so that it may be made of bar stock or steel tubing cut to size. The usual rivet set 5 is suitably retained in the forward end of the cylinder 40 and the valve mechanism 4 is mounted within the rear end of the cylinder which is closed by means of a screw plug 6 which may be readily removed when desired.

The handle 2 is preferably of the open 45 type comprising a hand portion 7 and a head portion 8 connected together by a single neck portion 9. Said head portion 8 has a longitudinal opening 10 therein of such diameter that the head will fit tightly 50 upon the rear end of the cylinder, and after

they have been completely machined and finished, the handle and cylinder are permanently secured together in any suitable manner as by welding, brazing or shrinking.

The piston 3 is of uniform diameter 60 throughout its length and is arranged to be inserted and removed through the forward end of the cylinder by merely removing the rivet set 5. Should the piston become fast in the cylinder for any reason, which 65 frequently happens in use, the screw plug 6 may be readily removed and a suitable tool inserted from the rear end of the cylinder to loosen the piston and remove it from the cylinder.

70 The valve mechanism 4 of the hammer, which is mounted within the rear end of the cylinder 1, comprises a valve casing 11 and a tubular valve member 12. The casing is 75 tubular in form and mounted in an enlarged bore 11^a in the cylinder forming a shoulder 11^b against which the inner end of the casing is held by the screw plug 6. The valve member is also tubular in form and is 80 slideable in the casing and arranged to receive the piston 3. Said valve casing is made in two sections for two reasons. The first is that it may be more cheaply manufactured, as hereinafter set forth, and the second is that it may be readily inserted into or removed from the cylinder, after the handle and cylinder have been permanently secured together into a one-piece structure, without unduly lengthening the hammer by extending the hand or grasping portion 7 of the 90 handle rearwardly a sufficient distance to permit an integral valve casing to pass between said grasping portion and the rear end of the cylinder.

95 At its rear end the valve casing has a series of ports 13 opening into the rear end of the cylinder and each leading from a passageway 14 in the casing, which in turn communicates at all times through a duct 15 and an annular groove 16 in the screw 100 plug 6 with a passageway suitably formed in the handle 2. Said passageway in the handle is connected with a source of pressure fluid supply and is controlled by a manually operable throttle valve 17. Preferably the passageway is formed by a plurality of drilled passageways 18, 18^a and 18^b, the passageways 18^a and 18^b being connected by an angular passageway 18^c formed in a plug 18^d which is provided to close the openings 110

left in the handle by the operation of drilling the passageway 18^a. A plug 18^e is also provided in the head of the handle to close the opening left by drilling the passageway 18^b.

The valve member 12 is arranged to control the admission of pressure fluid into the cylinder through the ports 13. Said valve member is preferably tubular in form, having a uniform internal diameter throughout its length equal to the bore of the cylinder. On its outer periphery said member is provided with a plurality of peripheral flanges 19 and 19^a, and 20 and 20^a, spaced apart and bearing upon the inner surface of the valve casing 11. The flanges 19 and 19^a are made somewhat larger than the flanges 20 and 20^a so as to have a greater area, for a purpose to be hereinafter set forth, and the inner surface of the valve casing is correspondingly made of different diameters to conform to the sizes of the flanges. Thus in the manufacture of the valve mechanism it becomes necessary to make the valve casing with a plurality of different internal diameters 12^a, 12^b and 12^c, the intermediate diameters 12^a and 12^b being larger than the diameters 12^c at the ends of the casing. It is difficult, however, to bore and grind such relatively large intermediate diameters, and I therefore form the valve casing in two separate sections each having only one of the intermediate diameters and an end diameter. It will be seen that each diameter of each of the sections is readily accessible to a tool inserted into the section. Preferably one of the sections is rabbeted as at 21 to receive the end of the adjacent section.

The rear end of said valve member is arranged to slide over the inner ends of the ports 13, and when the valve member is in its foremost position, as shown in Fig. 1, pressure fluid is admitted into the rear end of the cylinder and the piston is driven forwardly therein. The valve member is held in such position until the piston approximately reaches the forward end of the cylinder. The means for thus holding the valve member in its foremost position comprises a port 22 in the rear end of the valve casing and a series of ports 22^a in the valve member. The port 22 is in constant communication with the passageway 14 in the casing and thus with the pressure fluid supply, and the ports 22^a communicate with the cylinder when the piston travels forwardly in the cylinder. Said ports thus admit the pressure fluid to the rear surface of the flange 20^a, and the pressure fluid bearing thereon serves to hold the valve member in its foremost position until the piston 3 in its forward travel passes a pair of ports 23 opening into the cylinder substantially centrally thereof. Said ports communicate with a

longitudinal passageway 24 extending rearwardly in the cylinder, and said passageway 24 in turn communicates with a passageway 25 which admits pressure fluid to the forward side of the peripheral flange 19 of the valve member. As above stated, the flange 19 is made larger than the flange 20^a on the rear end of the valve member, so that the pressure area formed thereby is greater than that formed by the flange 20^a. Accordingly when the pressure fluid is admitted into the ports 23 by the passage of the piston forwardly in the cylinder it acts to shift the valve member rearwardly.

While the piston is traveling forwardly in the cylinder, air in the forward end thereof is permitted to escape to the atmosphere by means of the passageway 26 leading from the forward end of the cylinder rearwardly to the valve casing, where it communicates with a passageway 27 which opens into a groove 28 formed between the flanges 19^a and 20 on the valve member (Fig. 1). Said groove 28 in turn is arranged to discharge into a groove 29 in the valve casing and thence into a duct 30 leading through the valve casing, the cylinder, and the handle to the atmosphere.

The valve member having been shifted rearwardly to the position shown in Fig. 2, pressure fluid is admitted to the forward end of the cylinder to drive the piston rearwardly therein. To this end a passageway 31 leading from one of the pressure fluid supply ducts 15 in the screw plug 6 discharges pressure fluid into the groove 28 between the flanges 19^a and 20 on the valve member. This groove now communicates with the passageway 27 in the valve casing; the groove 29 in the valve casing leading to the exhaust duct 30 having been closed by the valve member when moved rearwardly, and the forward end of the passageway 31 having been opened by the valve member during such rearward movement thereof. Pressure fluid is thus admitted to the forward end of the cylinder and the piston is driven rearwardly in the cylinder.

As the piston moves rearwardly in the cylinder, the pressure fluid therein is permitted to exhaust from in front of the piston through a series of ducts 32 in the forward end of the valve casing, the inner ends of which ducts have been opened by the rearward movement of the valve member. Said ducts are arranged to discharge into the exhaust duct 30 leading to the atmosphere. 33 is a deflector over the exhaust duct 30 for directing the exhaust pressure fluid forwardly rather than radially of the cylinder.

When the piston in its rearward travel passes the ports 23 in the cylinder, the flow of pressure fluid being cut off from the for-

ward pressure area on the flange 19 of the valve member, enables the pressure fluid acting upon the rear pressure area on the flange 20^a to again shift the valve member 5 forwardly so as to admit pressure fluid into the rear end of the cylinder. In this position the valve member also cuts off the flow of pressure fluid through the passageway 31 to the forward end of the cylinder, and 10 establishes communication between the forward end of the cylinder and the exhaust duct 30. The parts are thus in position for another cycle of operation.

If additional pressure is needed to shift 15 the valve member rearwardly, a restricted passageway 34 may be provided in the valve casing, which passageway communicates constantly with the source of pressure fluid supply and conducts the pressure fluid to 20 the forward pressure area on the flange 19 of the valve member. This flow of pressure fluid, however, is not sufficient to interfere with the forward shifting of the valve member when the flow of pressure fluid through 25 the ports 23 is cut off.

It will be understood that the piston in its rearward travel, after passing the exhaust ducts 32, builds up sufficient pressure in the rear end of the cylinder to cushion the piston 30 ton in its rearward movement.

It will be apparent that the screw plug 6 serves to clamp the separate sections of the valve casing together within the rear end of the cylinder so that it forms in effect 35 an integral casing. At the same time the casing, as well as the valve member, may be readily removed from the cylinder without unduly lengthening the hammer by extending the hand or grasping portion of 40 the handle rearwardly. In this operation of removing the valve mechanism it is only necessary to unscrew the plug 6, and the rear section of the casing is first removed. Thereupon the valve member may be re- 45 moved and finally the forward section of the valve casing. This construction lends itself readily to a hammer in which the cylinder and handle form a one-piece structure, and at the same time the valve casing 50 may be more cheaply manufactured by reason of the increased facility with which the parts may be separately machined.

The method set forth of forming the passageway through the handle is advantageous in that all danger of restricting the passageway by forming the handle after the passageway has been drilled therein, is eliminated.

While I have herein set forth the invention with considerable particularity and especially the valve structure, it will be understood that the invention is not thus limited but that the structure set forth is merely illustrative of a preferred embodiment of the invention.

I claim as my invention:

1. A pressure-fluid-actuated tool having, in combination, a cylinder and a handle inseparably formed into a one-piece structure, said handle having a transverse hand portion spaced a short distance rearwardly of the cylinder, a piston operable in the cylinder, and valve mechanism for controlling the piston, comprising a valve casing mounted within the cylinder, said casing being of 75 a length greater than the space between the cylinder and said transverse hand portion of the handle and formed in separate sections so as to be removable from the rear end of the cylinder with the handle in position thereon.

2. A pressure-fluid-actuated tool comprising, in combination, a cylinder, a handle comprising a tubular portion constructed to fit snugly upon the rear end of the cylinder, and a transverse hand portion rigid with said tubular portion but spaced a short distance rearwardly thereof, said tubular portion of the handle being secured onto the rear end of the cylinder as by welding so as 80 to be permanently connected therewith in a one-piece structure, a piston operable in the cylinder, and valve mechanism for controlling the movements of the piston including a tubular casing mounted in the rear end of 95 the cylinder, said casing being formed in separate sections each of a length not greater than the space between the handle and the cylinder so as to be removable from the cylinder with the handle in position 100 thereon.

3. A pressure-fluid-actuated tool comprising, in combination, a cylinder and a handle inseparably formed into a one-piece structure, said handle having a transverse hand portion spaced a short distance rearwardly of the cylinder, a piston operable in the cylinder, valve mechanism for controlling the piston comprising a valve casing and a tubular valve member operable in the casing 105 in axial alignment with the cylinder and adapted to receive said piston in the movements thereof, and means for closing the rear end of said cylinder and clamping said valve casing in position therein, said casing 110 being formed in separate sections each of a length not greater than the distance between the cylinder and said transverse end portion of the handle, and said valve member being adapted to be removable from the rear end 115 of the cylinder after the rearmost section of the casing has been removed.

4. A pressure-fluid-actuated tool comprising, in combination, a cylinder and a handle inseparably formed into a one-piece structure, said handle having a transverse hand portion spaced a short distance rearwardly of the cylinder, a piston operable in the cylinder, valve mechanism for controlling the piston comprising a valve casing 125 130

made in two relatively short sections of substantially equal length and a tubular valve member operable in said casing, and means for closing the rear end of the cylinder and 5 clamping said valve casing in position therein, said casing and valve member being constructed to permit the removal from the

rear end of the cylinder, with the handle thereon, first of the rearmost section of the casing, then of the valve member, and finally 10 of the other section of the casing.

In testimony whereof, I have hereunto set my hand.

WILLIAM H. KELLER.
